FLEXIBLE BOBBIN RECEIVER AND
SUPPORT THEREFORRichard G. Turner, Worcester, Mass., assignor to
Crompton & Knowles Loom Works, Worcester,
Mass., a corporation of Massachusetts

Application December 22, 1945, Serial No. 636,945

6 Claims. (Cl. 139—255)

1

This invention relates to improvements in bobbin receivers for weft replenishing looms and it is the general object of the invention to provide a receiver including a bag which is supported and reinforced by a frame which holds it in normal position and by which it may be inverted to empty the bobbins in it.

It is customary to provide a bobbin collector for bobbins which are discharged from the shuttle during the weft replenishing operations. In an application filed on even date herewith I have set forth a bobbin receiver having a frame which supports a bobbin receiving bag the front part of which is connected to vertical members of the frame by lacing or the like. It is an important object of my present invention to construct the bag in such a way that it will be reinforced by the frame, more particularly the vertical members thereof which extend along the front corners of the bag.

The frame has a removable pivotal connection with a support fixed to the loomside and it is another object of the invention to construct this support in such manner that the lower part of the bag can move backwardly and forwardly between parts of the support when being placed in normal position or being removed for the purpose of emptying the bobbins.

The side members extend upwardly from the support and are then bent rearwardly to provide arms which support the top of the bag. The latter has hems which surround the vertical members but the latter should be reinforced in order to hold the bag in proper position to receive the discharged bobbins. It is another object of my present invention to connect the upper ends of the vertical members by a brace which can be applied to the frame after the bag has been put in position on the frame.

With these and other objects in view which will appear as the description proceeds, my invention resides in the combination and arrangement of parts hereinafter described and set forth.

In the accompanying drawing, wherein two forms of the invention are set forth,

Fig. 1 is a side elevation of a part of the loom, partly in section and showing the preferred form of my improved bobbin receiver in normal position.

Fig. 2 is a front elevation looking in the direction of arrow 2, Fig. 1.

Fig. 3 is an enlarged detailed front elevation of the support looking in the direction of arrow 3, Fig. 1.

2

Fig. 4 is a side elevation looking in the direction of arrow 4, Fig. 3.

Fig. 5 is an enlarged horizontal section on line 5—5, Fig. 1.

Fig. 6 is an enlarged front elevation looking in the direction of arrow 6, Fig. 1, and

Fig. 7 is a view similar to Fig. 6 but showing the modified form of the invention.

Referring particularly to Figs. 1 and 2, I have shown a loom frame 10 and a lay 11 supporting a shuttle box 12 which receives a shuttle S. During replenishing operations of the loom the exhausted or depleted bobbins are discharged downwardly from the shuttle and are guided forwardly by a bobbin chute 13 secured to the lay under the box 12. The bobbins are ordinarily discharged when the lay is at so-called front center or in the left hand position thereof as viewed in Fig. 1. During loom operation the chute 13 swings back and forth along a path under the shuttle box.

The receiver R for the discharged bobbins comprises essentially three parts, a stand 15, a metal frame F, and a cloth bag B. The stand or support 15 is secured to the loom frame as at 16 and projects outwardly therefrom, or to the right as viewed in Fig. 2. The support is formed with a bottom cross bar 17 and right and left uprights 18 and 19, respectively, as viewed in Fig. 3. Secured to the cross bar 17 is a bearing 20 opening upwardly and provided with a forwardly and upwardly inclined lip 21 which defines an elongated recess 22 with bar 17. Side stops 23 shown more particularly in Fig. 3 extend forwardly from the arms 18 and 19 at the ends of the recess 22. Secured to the top of each of the uprights 18 and 19 is a leaf spring 25 which projects forwardly and is upwardly bent as at 26.

The frame F is preferably made of a long piece 40 of tubing or the like bent to the general form shown in Figs. 1 and 2 so that it has right and left side members 30 and 31, respectively. These side members are joined at their bottom by an integral horizontal member or element 32 serving 45 the general function of a journal turnable in recess 22 and resting on bearing 20. The upper end of each of the side members is bent rearwardly and inclined downwardly to form a supporting arm 33.

Each side member 30 and 31 is provided near the lower end thereof with a fitting 35 formed with a lug or boss 36 for cooperation with the associated spring 25. The fittings 35 may be secured to their respective side members in any 55 approved manner as by soldering before the

frame F is bent at its upper end to provide the arms 33. The lugs or bosses 36 project outwardly from the vertical center of the frame F and are preferably in horizontal alignment, as are also the springs 25.

The bag B is made of cloth and has inner and outer side walls 37 and 38, respectively, a rear wall 39, and a front wall 40. These walls extend upwardly and provide the bag with an open bobbin receiving mouth M. Each of the inner and outer side walls is provided with upwardly extending straps or loops 41 through which the arms 33 extend, as shown in Fig. 1. Each vertical front corner of the bag is provided with an elongated hem 42 through which extends the associated side member 30 or 31. These hems extend downwardly a considerable distance along their side members and end in the vicinity of the upper ends of the uprights 18 and 19. The bottom of the bag extends rearwardly and downwardly from the hems and is attached by proper stitching to the side and front and back walls of the bag.

The upper ends of the side members 30 and 31 are preferably braced by some form of cross member which holds them in proper spaced relation and also adds rigidity to the frame F. In the preferred form of the invention each side member has sweated or otherwise secured thereto near the upper end thereof a fitting 45 located above the associated hem 42. These fittings have hubs 46 facing each other and threaded to receive the threaded ends of a cross bar or brace 47. The right and left hubs 46 are provided with opposite hand threads and the opposite ends of the cross brace 47 have opposite hand threads cut on them to fit the corresponding threads of the hubs. The cross bars 47 are fitted to the hubs after the bag is in position on the frame and then turned to establish tight holding connection with the side members 30 and 31 for the purpose of spacing the latter and strengthening the frame. Bar 47 is preferably bent forwardly as shown in Fig. 5 to provide a hand hold spaced forwardly of the wall 40 of the bag.

In the modified form of the invention shown in Fig. 7 fittings 50 are secured to the side members as in the preferred form, but the hubs 51 are soldered or otherwise secured to the ends of a cross brace 52 corresponding to the cross bar 47. In the modified form of the invention the cross bar 52 can be secured to the side members by an operation in which the heat is controlled to prevent burning of the bag.

In operation, the receiver R will ordinarily be in the position shown in Fig. 1 with the cross member 32 resting on the bearing 20 and in the recess 22. The side members 30 and 31 will extend substantially vertically upwardly and the lugs 36 will be under the springs 25 and held by them against the uprights 18 and 19 which cooperate with bearing 20 to hold frame F in normal position. The upper ends of the uprights 18 and 19 are free and define an open space 55 between them in front of the bottom of the bag. When the bag B is filled with depleted bobbins as the result of replenishing operations of the loom the attendant will grasp the cross bar 47 and swing the frame and bag forwardly around the bearing 20 as a center until the lugs 36 are forward of the front ends of the springs 25. At this time all parts of the receiver will be in front of the back and forth path traversed by the chute 13, and the receiver may now be lifted from the support 15 and inverted to empty the bobbins

contained therein. During this emptying operation the side members 30 and 31 support the forward part of the bag.

When the receiver is returned to normal position the cross bar 32 thereof is placed between the stops 23 and slipped down into the recess 22, after which the receiver is pushed rearwardly until the lugs 36 pass under the spring clips 25. The latter not only prevent upward movement of the receiver until after the latter has been moved forwardly of the path of the chute 13, but also assist gravity in holding the receiver in its normal position. During return movement of the bag to its normal position the lower part thereof will pass through the space 55 and assume the position shown in Fig. 1. The hems 42 are sufficiently wide to be slipped over the fittings 45 and 50 when the bag is attached to frame F.

From the foregoing it will be seen that I have provided a simple form of bobbin receiver including a rigid frame having side members which serve not only to support the bag but also reinforce it. It will also be noted that the uprights 18 and 19 have their upper ends unconnected to define a space 55 through which the bottom of the bag can move when the receiver is being removed from and returned to the loom.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom, a support fixed with respect to the loom, a cloth bobbin receiving bag having vertically extending hems, a frame to which the bag is attached mounted on said support, and spaced vertical side members on said frame extending through said hems to reinforce the bag.
2. In a weft replenishing loom, a support fixed with respect to the loom, a bobbin receiving bag having vertically extending hems formed on the front part thereof, and a frame to which the bag is attached removably mounted on said support, and having spaced side members extending through said hems, said side members reinforcing the bag when the frame is removed from said support and moved to a horizontal position.
3. In a bobbin receiver for a weft replenishing loom, a frame having vertically extending side members, an arm on the upper end of each side member extending rearwardly therefrom when the receiver is in working position relatively to the loom, and a flexible bobbin receiving bag suspended from said arms and having vertical hems surrounding said side members enabling the latter to reinforce the bag when the latter is turned to a horizontal position.
4. In a weft replenishing loom, a support fixed to the loom and having horizontally spaced upwardly extending uprights, a frame removably mounted on said support and normally extending along said uprights, and a bobbin receiving bag mounted on said frame and extending behind the latter and having the bottom thereof extending below the tops of said uprights and movable forwardly between the latter when the frame is removed in a forward direction from said support.
5. In a weft replenishing loom, a support fixed to the loom and having horizontally spaced upwardly extending uprights, a frame mounted on said support and movable backwardly and forwardly thereon and having side members normally extending along said uprights, and a bobbin

receiving bag supported on said frame and having the bottom thereof extending below the tops of said uprights and movable between said uprights when the frame is moved backwardly and forwardly with respect to said support.

6. In a weft replenishing loom, a support fixed to the loom having horizontally spaced upwardly extending uprights defining between them an unobstructed space, a frame mounted on said sup-

port for backward and forward movement relatively thereto and having side members normally extending along and supported by said uprights, and a bobbin receiving bag mounted on said frame and having the bottom thereof behind said space and movable through the latter when the frame is moved backwardly and forwardly with respect to said support.

RICHARD G. TURNER.
